UNITED STATES PATENT OFFICE.

JOHN W. MADDOX, OF JAMESTOWN, NEW YORK.

DEVICE FOR BRAZING.

SPECIFICATION forming part of Letters Patent No. 423,614, dated March 18, 1890.

Application filed July 24, 1889. Serial No. 318,476. (No model.)

To all whom it may concern:

Be it known that I, JOHN W. MADDOX, a citizen of the United States, residing at Jamestown, in the county of Chautauqua and State 5 of New York, have invented a new and useful Device for Brazing, of which the following is a specification.

This invention relates to devices for brazing together the ends of band-saws; and it has for 10 its object to provide a device for this purpose which shall be simple in construction, easily manipulated without the assistance of expert labor, and which shall be effective in operation.

15 The invention comprises a lamp forming the base of the machine and having two burners, one at each end, a clamping device to hold the saw arranged between the said burners, and a bellows and blow-pipe to blow the flames 20 in the direction of the saw for the purpose of melting the solder.

The invention further consists in the details of construction, which will be hereinafter fully described, and particularly pointed out 25 in the claims.

In the drawings hereto annexed, Figure 1 is a perspective view showing the device with the ends of a band-saw in position for being operated upon. Fig. 2 is a longitudinal ver- 30 tical sectional view. Fig. 3 is a sectional view taken vertically through the clamping device.

Like numerals of reference indicate like parts in all the figures.

35 1 designates the reservoir of a lamp, the top of which 2 constitutes the base of the device. The lamp is provided near each end with a burner 3, and at each end of the top is secured a bracket 4. To one of the brackets 4 is at- 40 tached a cup-shaped disk 5, over which is stretched a head or diaphragm 6, of rubber or other suitable elastic material. To the disk 5 is suitably connected a flexible tube 7, and blow-pipes 8 lead from the said disk through 45 perforations 9 in the brackets 4, and terminate at points opposite to the burners, the flames from which may thus be projected inwardly over the base of the machine.

Suitably mounted above and centrally upon 50 the base of the machine is a bracket 10, having outwardly-extending arms 11, provided at one of their sides with upwardly-extending

lugs 12. The arms 11 have rearwardly-extending projections 13, to receive thumb-screws 14, by means of which clamping-plates 55 15 may be forced downwardly against the faces or uppersides of the arms 11. Suitably pivoted to one side of the bracket 10 are a pair of levers 16 16, the inner ends of which extend between the arms 11, and are provided 60 with heads 17, having flat faces 18, that face each other, as shown. The outer ends of the levers are connected by means of a spring 19, which serves to force the heads 17 normally apart from each other.

Pivoted to the side of the bracket 11, between the levers 16 16, is a cam 20, having a lever or handle 21, by means of which it may be conveniently manipulated so as to force the outer ends of the levers apart from each 70 other, and thus bring the faces of the heads 17 closely together.

In operation the ends of a band-saw are first filed off slantingly in the usual manner, and they are then placed upon the upper sides of 75 the arms 11, slightlylapping over each other, and a piece of silver-solder being interposed between the overlapping ends of the saw. The ends of the saw are then secured by tightening the thumb-screws 14 and clamp- 80 ing-plates 15. The ends of the saw are held in alignment by placing the back of a saw against the upwardly-extending lugs 12 of the arms 11. The ends of the saw, as well as the interposed piece of solder, are washed with 85 acid in the usual manner. By blowing through the tube 7 air is now forced into the space between the cup-shaped disk 5 and the elastic diaphragm 6, which latter expands, and by again contracting serves to force the air 90 through the blow-pipes 8, by means of which the flames from the burners 3 3 are projected inwardly until they strike the point at which the ends of the saw are overlapped. Being thus subjected to intense heat, the solder will 95 be quickly melted and the ends of the saw raised to the required temperature, when the blowing is suspended and the cam-lever manipulated so as to bring the faces of the heads 17 together, clamping and tightly compressing the ends of the saw, which will thus be accurately and firmly joined. At the same time the comparatively low temperature of the disks or heads 17 will chill the ends of 100

the saw, which are thus caused to retain their temper.

The operation and advantages of this invention will be readily understood from the foregoing description, taken in connection with the drawings hereto annexed. The construction is simple and inexpensive, and the device may be successfully manipulated without the assistance of skilled labor.

10 Having thus described my invention, what I claim, and desire to secure by Letters Patent, is—

15 1. In a device for brazing band-saws, the combination of a lamp having two burners, a bracket mounted upon the same between said burners, and having outwardly-extending horizontal arms provided with upwardly-extending lugs, and clamps adapted to be forced down against the faces of said arms, substantially as set forth.

20 2. In a device for brazing band-saws, the combination of a lamp having two burners, a bracket mounted upon the same between said burners, and having outwardly-extending arms provided with upwardly-extending lugs, clamps adapted to be forced down against the faces of said arms, and blow-pipes arranged to project flame between the inner ends of the said arms, substantially as set forth.

25 3. In a device for brazing band-saws, the combination of a lamp having two burners, a bracket mounted upon the same between said burners, and having outwardly-extending arms provided with clamping devices, arms or brackets mounted adjustably upon the ends of the lamp, a bellows or air-compressing device attached to one of said brackets, and blow-pipes extending from said air-

30 compressing device through guide openings or perforations in the said brackets, substantially as set forth.

35 4. In a device for brazing band-saws, the combination of a lamp, a bracket mounted upon the same and having outwardly-extending arms provided with lugs and clamping devices, a pair of levers connected pivotally to

one side of the said bracket and extended inwardly between the said arms and provided with heads having flat meeting faces, a spring 50 to force the inner ends of said levers normally apart, a cam-lever mounted pivotally between said clamping-levers and adapted to force their inner ends together, an air-compressing device, and blow-pipes arranged 55 to project flame between the inner ends of the horizontal saw-supporting arms, substantially as set forth.

5. In a device for brazing band-saws, the combination of a lamp having a burner at 60 each end, a bracket arranged intermediately between said burners and having outwardly-extending arms provided with lugs and clamping devices, the clamping-levers pivoted to said bracket and extending inwardly 65 between said arms, a cam-lever to operate the said clamping-levers, brackets mounted adjustably at each end of the lamp, a bellows or air-compressing device attached to one of the said brackets, and blow-pipes extending 70 from said air-compressing device through guide-openings in the said bracket and terminating adjacent to the outer sides of the burners, substantially as and for the purpose set forth. 75

6. In a device for brazing band-saws, the combination, with clamps for holding the ends of the saw while being heated, of flat-faced clamps adapted to compress and chill the ends of the saw after being raised to the 80 required heat, said clamps being mounted between the burners of a lamp which is provided with blow-pipes, and an air-compressing device for projecting flame in the direction of the holding-clamps, substantially as 85 set forth.

In testimony that I claim the foregoing as my own I have hereto affixed my signature in presence of two witnesses.

JNO. W. MADDOX.
